CLAIM

The ornamental design for a gas pump handle holder, as shown and described.

DESCRIPTION

FIG. 1 is a perspective view of my design;

FIG. 2 is a front elevational view of my design, the opposite side view being a mirror image thereof;

FIG. 3 is a side view of my design, the opposite side view being a mirror image thereof; and,

FIG. 4 is a top view of my design, the opposite side view being a mirror image thereof.

The features shown in broken lines in FIG. 1 are shown for illustrative purpose only and form no part of the claimed design.
